UNITED STATES PATENT OFFICE.

WILLIAM EDWARD BOEHCK, OF JERSEY CITY, NEW JERSEY, ASSIGNOR TO REVOLATOR COMPANY, OF JERSEY CITY, NEW JERSEY, A CORPORATION OF NEW JERSEY.

ELEVATOR SAFETY APPARATUS.

1,373,944.

Specification of Letters Patent.

Patented Apr. 5, 1921.

Application filed August 1, 1919. Serial No. 314,644.

To all whom it may concern:

Be it known that I, WILLIAM EDWARD BOEHCK, a citizen of Germany, residing at Jersey City, in the county of Hudson and State of New Jersey, have invented certain new and useful Improvements in Elevator Safety Apparatus, of which the following is a specification, reference being had to the accompanying drawings.

10 This invention relates to improvements in safety devices for elevators and particularly to improvements in safety devices for tiering machines (otherwise known as portable elevators), the purpose of which devices is to prevent the dropping of the load-carrying platform, in case the hoisting-cable should break; and an object of this invention is to provide a safety device of the kind just mentioned, which will be simple in construction, comparatively cheap in manufacture, and efficient and durable in operation and use, and the cost of repairs of which will prove small. Another object of this invention is the provision of means whereby 20 the engagement of the holding cams with the elevator-standards is prevented or obviated, in case the operator should slacken the hoisting cable sufficiently, when the platform has been lowered so that the same rests 30 upon the bottom structure or base of the elevator.

In the drawings illustrating the principle of this invention and the best mode now known to me of applying that principle, 35 Figure 1 is an elevation of so much of a tiering machine as is necessary to illustrate this invention; Fig. 2 is a side view, looking in the direction of the arrows in Fig. 1, the view being partly in section on the line 2-2 of Fig. 1; and Figs. 3 and 4 are details illustrating the toothed holding or clutch cam in side and front elevation, respectively.

As is conventional in structures of this 45 class, the tiering machine is provided with a pair of uprights or standards *a*, which are made of channel-iron or of steel, as may be preferred. There is one of these standards *a* at each side of the tiering machine; 50 and each standard *a* comprises a web *a'* from each vertical edge of which there projects inwardly a flange *a''*, thereby giving to the standard *a* its channeled form. The load-receiving platform *b* is (as is shown in 55 Fig. 2) horizontally disposed and is carried

by the U-shaped lifting-frame or guide-frame *c* that consists of a pair of upright guide-arms *c'*, the lower ends of which are connected by a cross-beam *c''*. A pair of inclined braces *c''* (Fig. 1) joins the latter 60 with each of the arms *c'*. When the lifting-frame *c* is raised, it carries with it the load-receiving platform *b*. From the upper end of each arm *c'*, there extends laterally and outwardly a stub-shaft or arbor *d*, which 65 projects into the channel of the opposed machine-standard *a* and upon which is rotatably mounted a guide-roller *e*. The flanges *a''* of the machine-standard *a* serve as tracks upon which the guide-roller *e* travels. The 70 lower end of each arm or upright *c'* of the lifting-frame *c* is similarly provided with an outwardly and laterally projecting roller-shaft *d'* upon which turns a lower guide-roller *e'* that runs on the flanges *a''* as 75 tracks in the same manner as does the upper guide-roller *e*.

Horizontally disposed beneath the rigid cross-bar *c''* of the lifting-frame *c* there is a loose hoisting cross-beam *f* to the front 80 and rear faces of which there are fastened, by means of the pin *g*, the lower ends of a pair of pull-straps or pull-links *h*, which extend upwardly from the loose cross-bar *f* and between which lies the rigid cross-bar 85 *c''* of the load-carrying platform *b*. The lower end of the hoisting-cable *i* enters between the upper ends of the pull-links *h* and is formed with a loop *i'*, through which and these upper ends passes a pin *j*. The other 90 end of the hoisting cable *i* is wound around the windlass-drum (not shown) of a hoist, in a well-known manner; and, when this drum is turned, the cable *i* is either wound up or paid out, whereby the loose cross-beam 95 *f* is either raised or lowered away and the load-carrying platform *b* is either lifted or allowed to descend.

From near the middle of each guide-arm *c'*, and between the roller-carrying shafts *d*, *d'*, 100 there extends laterally and outwardly a cam-carrying shaft *k* which projects into the channel of the opposed machine-standard *a* and upon which there is mounted, free to swing, a holding or clutch cam *m* of an almost semi-circular shape (Figs. 3 and 4). The hole *m'* through which passes the pivot or shaft *k* is eccentrically located in the holding-cam *m*; and, from the top of the latter, there extends upwardly an ear *m''* 110

formed with a perforation m^x . The convex face n of the cam m is beveled or inclined from one of its edges to the other thereof, in order that the face n may conform to the bevel or inclination of the opposed face of the flange a'' of the machine-standard a ; and, in order to allow for the inaccuracies or inequalities of the bevel of this opposed face, the face n of the cam m is slightly rounded.

10 Ratchet teeth n' are formed in the face n for the purpose of increasing the gripping action of the cam m , when the latter is thrown against the flange a'' opposed thereto. From the ends of the loose lifting cross-beam f , there project horizontally the lugs f' the free ends of which are perforated to receive the lower ends of the Z-shaped link-rods o . The upper end of each link-rod o is fitted into the perforation m^x formed in the ear m'' of the cam m ; and when the loose hoisting cross-beam f moves downwardly with relation to the platform cross-beam c'' , the connecting link-rods o transmit the motion and rock the two holding cams m on their pivots or shafts h , so that the toothed cam-faces n are pressed into clutching engagement with and against the beveled faces of the flanges a'' of the machine-standards a and there results a frictional gripping action of the cams m therewith. At each side of the machine, there is provided a coil-spring p the lower end of which is attached to the adjacent guide-arm c' and the upper end of which is fastened to that end of the connecting-rod o which enters the ear m'' of the cam m on that side of the machine (Fig. 1). These coil-springs p tend to throw the connecting-rods o downwardly and cause the same promptly to follow any drop of the loose cross-beam f relatively to the fixed cross-beam c'' of the platform b and thereby to insure quick action of the clutch-cams m .

45 The operation of the safety contrivance described hereinbefore may be briefly set forth as follows and will be readily understood. So long as the hoisting mechanism of the tiering machine operates normally, the pull of the hoisting-cable i (acting in one direction) and the weight of the platform b and the load thereon (acting in the opposite direction) hold the two horizontal cross-bars c'', f , firmly pressed together and maintain the clutch-cams m in the full-line 50 (or inoperative) position shown in Fig. 2, against the tension of the coil-springs p . When, however, the hoisting-cable i breaks, the loose cross-beam f will drop relatively to the rigid or fixed cross-beams c'' of the 55 platform guide-frame c and will fall away therefrom, the coil-springs p will contract and the holding-cams m will be rocked on their pivots h so as to force their toothed cam-faces n into frictional clutching contact 60 with the opposed faces of the flanges a'' of

the standards a . The result of the rubbing of the toothed faces n of the cams m against the flanges a'' is that the eccentrically-mounted cams m are given a rolling motion and the guide-rollers e are forced with intense pressure against the opposite face of the flanged channel-beam a , whereby great frictional resistance to the downward movement of the platform b is produced and the same is brought to rest and held up, 75 despite the rupture of the hoisting-cable i .

It is to be observed that the cams m are mounted, and therefore act, independently of each other, whereby the stresses produced by the sudden throwing of the weight of the platform and the load thereon upon the standards a are distributed between the latter, instead of being concentrated upon a single standard, which concentration results in those cases in which the holding-cams are 80 mounted on a common shaft and hence are compelled to act in unison, and when the structural shapes a differ slightly from each other in form and dimensions of the channel and its walls, a difference that is practically always to be found in the structural shapes a as they are commercially produced and marketed. Due to such slight inequalities, one of the cams m will engage before the other; and, if the two cams were mounted on 85 a common shaft, one cam would almost surely come into gripping action, while the other would not engage effectively with the flange a'' of the guide-standards a , from which it would result that the standard a upon which 90 the load would be thrown would be forced to sustain the weight alone or to collapse. Of course, when the collapse of the standard takes place, the disaster that follows is greater by far than if the loaded platform b 95 were to drop; and such collapse is very liable to occur, particularly in case the platform b is loaded to the capacity of the machine.

Should the operator permit the hoisting-cable i to become slack, while the platform b is resting upon the bottom-structure or base q of the elevator, the holding-cams m are liable to be thrown into frictional engagement with the standards a . In order to obviate such engagement under the conditions just mentioned, the following arrangement of parts is provided, namely: From the loose lifting cross-beam f , there extends or projects downwardly a pair of posts or bolts r the lower ends of which are threaded and pass through holes formed in a horizontal bar s arranged parallel to the lifting-beam f . The bar s is held on the posts or guide-bolts r by means of the nuts t that are screwed on 110 the projecting threaded ends of the posts r . Mounted on the latter and interposed between the lifting-beam f and the bar s , there are compression-springs u which tend to hold the bar s against the nuts t and, there- 115 120 125 130

fore, at a fixed distance from the lifting-beam *f*. Fixed in position between the guide-standards *a* and arranged to intercept the bar *s* in its downward travel at just the 5 same instant as the platform *b* comes to rest upon the elevator-base *q*, there are the stop-brackets *v*. When, therefore, the platform *b* rests upon the elevator-base *q* and the hoisting-cable *i* is slackened, the lifting-beam *f* and the platform-cross-bar *c''* will 10 nevertheless be found to be held firmly pressed together by the tension of the coil-springs *u*, the bar *s* bearing upon the stop-brackets *v* at this time; and the holding-cams *m* will be maintained in their normal 15 or inoperative position. Should the hoisting-cable *i* become slack (as in case of the rupture thereof), while the platform *b* is above the elevator-base *q* and the bar *s* is 20 above the stop-brackets *v*, the lifting-beam *f*, the bar *s*, guide-posts *r* and coil-springs *u* will, as a unit, fall away from the platform crossbar *c''*, thereby throwing the holding-cams *m* into frictional engagement with the 25 faces of the flanges *a''* of the guide-standards *a* in the manner and by the means already fully described hereinbefore.

This application is filed as a continuation in part of my pending application, Serial 30 No. 304875, filed June 17, 1919.

I claim:

1. Elevator safety apparatus for tiering machines, including a hoisting mechanism; a pair of fixed standards; a load-carrying platform mounted to travel therebetween; platform-guiding rollers arranged to travel along said standards; a lifting-beam below said platform and supported by said hoisting mechanism, said lifting-beam being free 35 to move downwardly relatively to said platform in case said hoisting mechanism ceases to support said lifting-beam; cams mounted free to turn independently of each other and arranged to travel in close proximity to said 40 standards; and cam-actuating devices connecting said cams and lifting-beam and arranged to throw said cams into frictional engagement with said standards when said lifting-beam falls relatively to said platform, whereby said platform-guiding rollers 45 are forced into frictional engagement with said standards and the platform is held from dropping.
2. Elevator safety apparatus for tiering machines, including a hoisting mechanism; 50
3. Elevator safety apparatus for tiering machines, including a hoisting cable; a pair of fixed standards; a load-carrying platform mounted to travel therebetween; a lifting-beam below said platform and attached to said hoisting cable, said lifting-beam being free to move downwardly relatively to said platform in case said cable should become slack; devices for preventing the fall of said 55 platform when said cable becomes slack or ruptures, said devices being thrown into operation by the fall of said lifting-beam; and mechanism for preventing the operation of said devices when the platform is supported otherwise than by the hoisting cable.
4. Elevator safety apparatus for tiering machines, including a hoisting cable; a pair of fixed standards; a load-carrying platform mounted to travel therebetween; a lifting-beam below said platform and attached to said hoisting cable, said lifting-beam being free to move downwardly relatively to said platform in case said cable should become slack; devices for preventing the fall of said 60 platform when said cable becomes slack or ruptures, said devices being thrown into operation by the fall of said lifting-beam; and mechanism for holding said lifting-beam and platform against separation from each other in case they are supported otherwise than by said cable.

Signed at Jersey City, New Jersey, in the presence of the two undersigned witnesses this 23rd day of July, A. D. 1919.

WILLIAM EDWARD BOEHCK.
